UNITED STATES PATENT OFFICE.

ALBERT EDWARD JONES, OF WESTMINSTER, LONDON, ENGLAND, ASSIGNOR TO THE
WHITEHEAD TORPEDO COMPANY LIMITED, OF WESTMINSTER, ENGLAND.

RADIAL CYLINDER ENGINE.

Application filed March 20, 1924; Serial No. 700,644, and in Great Britain December 21, 1923.

This invention relates to radial cylinder engines particularly the compressed air engines of automobile torpedoes.

According to the invention the engine 5 comprises two series of radial cylinders (four in each series for example) arranged in separate planes transverse to the axis of the crank shaft and so disposed that the valve casings or chests of each of the two 10 series of cylinders are situated in the spaces between the cylinders of the other series. In this manner a particularly compact engine is provided as its overall length does not materially exceed that of an engine having 15 half the number of cylinders. It will be understood that a developed plan of the improved engine shows the cylinders arranged in staggered formation and the valve casings arranged in similar formation 20 with the outer parts of the valve casings projecting only slightly, if at all, beyond the outer portions of the cylinders.

The pistons working in the two series of cylinders operate on two cranks set at 180° 25 apart; these cranks are preferably made integral with each other and with the balanced crank webs and in this case the usual segmental crank pin bearings or brasses engaging in lateral recesses formed 30 in the crank cheeks are divided in a plane transverse to the axis of the crank shaft and after being slipped into position one half at a time, are connected together by bolts or screws passing through projections or 35 studs on the segmental bearings or brasses and through tubular connecting rod ends in which these projections or studs fit.

The valves are preferably of the poppet type and may be actuated by cams formed 40 on the crank webs, the valves of one series of cylinders being actuated by a cam on the web of the crank pin appertaining to the other series and the valves of the latter series being actuated by a cam on the web 45 of the crank pin appertaining to the first-mentioned series. Alternatively the movement of each of the pistons is utilized for operating, through a lever (one for each cylinder), the valve of the cylinder immediately behind that to which the piston re-

lates, the ends of the said levers remote from the ends that co-operate with the valve stems being acted upon, in order to open the valves, by the pistons or the gudgeon pins at a predetermined position of each piston 55 during its outward movement from the cylinder. Ordinarily with such an arrangement any variation of the lead will produce a variation of the point of cut off; this is not always desired and in these circumstances 60 the gudgeon pins may be recessed or slotted in such a manner that at a predetermined point in the outward movements of the pistons the recesses or slots come opposite bent ends of the levers and permit the valves 65 to close, the co-operation of the unrecessed or unslotted portions of the gudgeon pins with the said bent ends having effected the opening of the valves. In this manner the closing of the valves can be made to take 70 place at any predetermined point irrespective of the point of opening.

In order that the said invention may be clearly understood and readily carried into effect, the same will be more fully described 75 with reference to the accompanying drawings, in which:

Figure 1 is an end elevation, with the upper part in section on the line 1, 1 of Figure 2, of a compressed air engine constructed in accordance with this invention.

Figure 2 is a section taken approximately on the line 2, 2 of Figure 1.

Figure 3 is a developed plan of the cylinders and valve casings.

Figure 4 is a view similar to the upper part of Figure 1 showing an alternative arrangement for operating the valves, and

Figure 5 is a view showing another arrangement for operating the valves.

A, A, A, A are the four cylinders of one series, A¹, A¹, A¹, A¹ are the valve casings or chests appertaining to these cylinders and a¹ . . . are the valves in these casings. B, B, B, B, are the four cylinders of the other series, B¹, B¹, B¹, B¹ are the valve casings or chests appertaining to the latter cylinders and b¹ . . . are the valves in the latter casings. It will be observed from Figure 3 that the valve casings of each of 100

the two series of cylinders are situated in the spaces between the cylinders of the other series. In this figure C, C, C, C, represent compressed air inlet pipes and the 5 ducts leading the compressed air from these pipes to the valve casings are represented by the thick lines between the said pipes. The exhaust air from the cylinders escapes through holes in the cylinder walls 10 (some of these holes being shown at a^{xx} in Figures 1 and 4) when the pistons reach the end of their outward strokes. It will be seen from Figure 3 that the outer parts of the valve casings do not project beyond 15 the outer portions of the cylinders.

Each piston a is connected by a gudgeon pin a^2 to a connecting rod A^2 which is made tubular as shown so that the lower end can receive semi-cylindrical projections or studs 20 a^3, a^3 on divided segmental brasses A^3, A^3 for the crank pins A^x, B^x . These crank pins are set at 180° apart and are made integral with each other and with balanced crank webs a^x, b^x . The said divided segmental brasses engage in lateral recesses formed in the crank cheeks as shown in Figure 2 and are slipped into position one half at a time, it being understood that the arcuate lengths 25 of the said brasses are such as to allow the last half of the fourth brass to be slipped into position when the previous three complete brasses and the first half of the fourth brass have been placed in position, there being sufficient room between the first brass 30 and the first half of the fourth brass for the second half of the latter brass to be inserted; this second half is then moved sideways into engagement with its lateral recess and then moved circumferentially into place by the side of the first half, or conversely the latter half is moved circumferentially into place by the side of the second half. The assembled brasses are connected to the connecting rods 35 by lifting the latter and engaging their ends over the projections or studs a^3, a^3 and then passing a bolt or screw a^{xx} through holes in the said projections or studs and in the tubular end of the connecting rod.

The crank pins A^x, B^x and their brasses are lubricated from axial bores a^4, b^4 (Figure 2) in the crank pins, which bores are supplied with oil by centrifugal action through holes in the crank web communicating with a small central chamber A^4 in this web, oil being supplied to this chamber under pressure in any suitable manner.

The valves $a^1 \dots, b^1 \dots$ are of the spring controlled poppet type and may be opened in any of the three ways shown in 60 Figures 1 and 2, Figure 4 and Figure 5. Referring to Figures 1 and 2 it will be seen that the valves $a^1 \dots$ are opened by a cam b^0 on the crank web b^x and the valves $b^1 \dots$ are opened by a cam a^0 on the crank 65 web a^x , these cams operating upon the valve

stems through interposed tappet levers $a^{1x} \dots, b^{1x} \dots$, the former tappet levers appertaining to the valves a^1 and the others to the valves b^1 . In Figure 4 the valve b^1 is lifted by a bell-crank lever b^2 the free 70 end of which is arranged in the path of the gudgeon pin a^2 (or of part of the piston) appertaining to the cylinder A so that the downward movement of the piston a effects the lifting of the valve b^1 which appertains 75 to the cylinder B immediately behind the cylinder A. The other valves b^1 are opened in a similar manner (each valve having its separate bell-crank lever) and the valves a^1 are also similarly opened by bell-crank 80 levers operated by the pistons of the cylinders B . . . . In this construction any variation of the point of cut off will produce a variation of the point of cut off and vice-versa.

Figure 5 shows a construction in which 85 the closing of the valves can be made to take place at any predetermined point irrespective of the point of opening, this result being obtained by forming the gudgeon pin a^2 with a recess or slot a^{2x} in such a manner 90 that at a predetermined point the recess or slot comes opposite the bent end b^{2x} of the bell crank lever b^2 and allows the valve to close at the desired interval after the valve has been opened by the co-operation of the 95 un recessed or unslotted portion of the gudgeon pin with the said bent end. It will be understood that each of the valves is operated in a similar manner through separate bell-crank levers, the valves a^1 being operated by the gudgeon pins relating to the 100 cylinders B . . . .

Although the engine above described with reference to the drawings is intended to be operated by compressed air, it is to be understood that with suitable modifications of a 105 constructional nature it would operate as an internal combustion engine.

What I claim and desire to secure by Letters Patent of the United States is:— 110

1. In a radial cylinder engine, the combination of a series of radial cylinders, a second series of radial cylinders arranged in a plane parallel to that containing the first series, the cylinders in the two series being disposed in staggered formation, a series of valve casings appertaining to the first series of cylinders and situated in the spaces between the cylinders of the second series and a series of valve casings appertaining to the second series of cylinders and situated in the spaces between the cylinders of the first series. 115 120

2. In a radial cylinder engine, the combination of a series of radial cylinders, a second series of radial cylinders arranged in a plane parallel to that containing the first series, the cylinders in the two series being disposed in staggered formation, a series of valve casings appertaining to the 125 130

first series of cylinders and situated in the spaces between the cylinders of the second series, a series of valve casings appertaining to the second series of cylinders and situated in the spaces between the cylinders of the first series, poppet valves in said valve casings, a cam on the web of the crank pin

appertaining to the first series of cylinders for lifting the second series of valves, and a cam on the web of the crank pin appertain-¹⁰ing to the second series of cylinders for lifting the first series of valves.

ALBERT EDWARD JONES.
